UNITED STATES PATENT OFFICE.

JOHN P. FARMER, OF PORTLAND, OREGON, ASSIGNOR OF ONE-HALF TO
CHARLES F. ADAMS, OF SAME PLACE.

AUTOMATIC CUT-OFF PILOT-BURNER.

SPECIFICATION forming part of Letters Patent No. 645,168, dated March 13, 1900.

Application filed November 12, 1898. Serial No. 696,268. (No model.)

To all whom it may concern:

Be it known that I, JOHN P. FARMER, a citizen of the United States, residing at Portland, in the county of Multnomah and State of Oregon, have invented a new and useful Gas-Burner, of which the following is a specification.

My invention relates to gas-burners of that class used for illuminating purposes, and particularly to a by-pass and pilot-burner, whereby under certain conditions a continuous flame is provided at the pilot-burner to cause the lighting of the gas at the main burner when the main supply is opened; and the object in view is to provide automatic means for controlling the passage of gas through a by-pass to the pilot-burner to prevent the useless escape of the gas and yet insure a flame sufficient to ignite gas at the main burner when required.

In the usual construction of thermostatic valve-controlled means the thermostatic element has not been operated by the heat of a main burner, but instead, in order to initially operate the valve-controlling means corresponding to the pilot-burner-controlling mechanism of the present construction, it has been necessary to heat the thermostatic parts by means of a match or other igniting device, this operation consuming some time and entailing much annoyance. In the present construction there are provided a main burner and a pilot-burner, of which the pilot-burner has thermostatic controlling mechanism, the thermostatic element extending into the zone of heat of the main burner, so that it is only necessary to light the main burner in the usual manner, when the pilot-burner will be opened, and the gas therefrom will be ignited by the main-burner flame. Thus the pilot-burner is initially opened by means of the heat from the main burner, the heat of the pilot-burner being sufficient to maintain it open after the flame at the main burner has been extinguished.

Further objects and advantages of this invention will appear in the following description, and the novel features thereof will be particularly pointed out in the appended claims.

In the drawings, Figure 1 is a view of a burner constructed in accordance with my in-

vention, the same being shown in connection with a mantel and chimney of the ordinary construction and arrangement, which, however, are indicated in dotted lines. Fig. 2 is 55 a sectional view of the same. Fig. 3 is a section on the plane indicated by the line 3 3 of Fig. 1, the plane of the section upon which Fig. 2 is taken being indicated by the line 2 2 of Fig. 3. Fig. 4 is a detail view, partly in 60 section, of a pilot-burner having a slightly-modified construction of means for varying the relative positions of the valve and seat. Fig. 5 is a detail view of still another modified construction of valve and seat adjusting 65 devices.

Similar reference characters indicate corresponding parts in all the figures of the drawings.

The main burner 10, which is carried by the 70 supply-pipe or bracket-arm 11, may be of any ordinary or preferred construction, that which is indicated in the drawings being of a type adapted to be employed in connection with an incandescent mantel 12 and chimney 13, 75 (indicated in dotted lines,) said main burner having a valve or key 14 for controlling the communication of gas to the burner.

In communication with the main gas-supply channel of the burner, in front of the 80 controlling valve or key and preferably formed in a lateral enlargement 15 of the main burner, is a channel 16, forming a by-pass, through which gas is adapted to flow, whether the controlling valve or key 14 is 85 open or closed. In order that the flow of gas through this by-pass may be regulated, I preferably employ a regulating-valve 17, provided with a threaded stem 18, which may be constructed in the form of a screw with a 90 kerfed head 19. This regulating-valve is disposed in operative relation with a valve-seat 20, which in the construction illustrated is formed in the inlet end of the by-pass, whereby the regulating-valve operates transversely 95 of the main gas-channel and may be manipulated to allow the desired quantity of gas to escape laterally from said main channel. Also carried by the lateral extension 15 and in communication with the by-pass 16 is a 100 thermostatic pilot-burner 21, constructed of hard brass or other equivalent material which

is expansible when heated. In the construction illustrated this pilot-burner consists of a tube threaded or otherwise removably fitted at its lower extremity in a socket 22, 5 formed in the above-described lateral burner extension 15, said socket in turn being in communication with the by-pass 16, and said burner-tube terminates at its upper end in a reduced burner orifice or outlet 23, which is 10 adapted to supply only sufficient gas to support a thin pencil-like flame, which, being located adjacent to the main-burner outlet, is in position to ignite gas escaping from the main-burner outlet. Also located in the 15 burner-tube 21 at a suitable point, preferably near the orifice 23, is a controlling-valve seat 24, and in operative relation therewith is a controlling-valve 25, carried by a stem 26, which is secured to and supported by the 20 lateral extension 15, said controlling-valve stem being constructed, preferably, of neutral steel or other material which is practically unaffected by heat or of which the ratio of expansion when subjected to heat is less 25 than that of the tube forming the pilot-burner, whereby when the pilot-burner is exposed to heat, due either to a flame at the main burner or at the orifice of the pilot-burner, the tube will be expanded longitudinally to a sufficient degree to remove the seat 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880

valve when the burner shell or tube is cooled or is unaffected by heat at either of the burners and also to secure the efficient unseating 70 of said valve when the burner shell or tube is heated by a flame at either of the burners, a variety of means may be employed; but in the construction illustrated in Figs. 1 and 2 I have threaded the lower extremity of the 75 regulating-valve stem 26 into a suitable guide 27, formed in the bottom of the socket 22 and provided at its extremity with a key or wrench seat 28, and also have threaded a lock-nut 29 upon the exposed extremity of 80 said stem to secure the latter at the desired adjustment. This rod forming the valve-stem 26 may be adjusted axially to vary the position of the valve with relation to the seat 85 24 by applying a wrench or key to the seat 28, the lock-nut 29 previously being loosened. In Fig. 4, however, I have illustrated a slightly-modified construction of means for adjusting the relative positions of the controlling-valve and seat, wherein the burner- 90 tip 30, in which is formed the gas-orifice 23^a, is threaded upon the pilot-burner shell or tube 21^a and carries the valve-seat 24^a for adjustment toward and from the controlling- 95 valve 25^a, the lower end of the valve-stem 26^a being fixed in the lateral burner extension 15^a, and in Fig. 5 I have illustrated another modification of these adjusting devices, wherein the separate pilot-burner tip 30^a is threaded within the burner shell or tube 21^b. In either case the valve and its seat are relatively adjustable to secure an efficient seating of the valve when the burner shell or tube is not exposed to heat due to a flame at either of the burners.

The automatic operation of the controlling-valve for the pilot-burner will be readily understood from the foregoing description, and it will be seen that to initially open the pilot-burner there is no more labor or time expended than in lighting the usual burner where no thermostatic closure is involved. It will be obvious, furthermore, that various changes in the form, proportion, and the minor details of construction may be resorted 110 to without departing from the spirit or sacrificing any of the advantages of the invention.

Having described my invention, what I claim is—

1. The combination with a main burner having a by-pass, an adjacent pilot-burner having a shell communicating with the by-pass, a controlling device for the pilot-burner comprising a valve and a seat, and a thermostatic element connected with one member of the controlling device and extending into the zone of heat of the main burner to be energized to operate the controlling device.
2. The combination of a main burner having a communicating by-pass, an adjacent pilot-burner having a thermostatic shell communicating with said by-pass and extending into the zone of heat of the main burner to be

energized thereby, a valve-seat carried by the shell, and a fixed valve adapted to seat and unseat with respect to said valve-seat as the shell contracts and expands to control the by-pass.

3. The combination of a main burner having a communicating by-pass, an adjacent pilot-burner communicating with said by-pass and having a thermostatic shell extending into the zone of heat of the main burner to be energized and carrying a valve-seat, and a fixed outlet-controlling valve arranged in operative relation with said seat, substantially as specified.

4. The combination with a main burner, of a by-pass in permanently-open communication with the supply-channel of the main burner, an adjacent pilot-burner having a thermostatic shell in communication with said by-pass and having a valve-seat, said shell extending into the zone of heat of the main burner to be energized, and a valve arranged in operative relation with said seat carried by the shell, substantially as specified.

5. A main burner having a supply valve or key and a lateral by-pass uncontrolled by the key, a pilot-burner having a thermostatic shell carried by the main burner in communication with said by-pass, said shell extending into the zone of heat of the main burner to be energized, and a controlling-valve arranged in operative relation with a seat in said thermostatic shell, substantially as specified.

6. The combination with a main burner having a supply valve or key and a by-pass, of an adjacent pilot-burner supported by the main burner in communication with said by-pass and having a thermostatic shell extending into the zone of heat of the main burner to be energized, controlling-valve mechanism actuated by said thermostatic shell, and a regulating-valve for the by-pass, substantially as specified.

7. The combination with a main burner having a supply valve or key and a by-pass, of an adjacent pilot-burner supported by the main burner in communication with said by-pass and having a thermostatic shell extending into the zone of heat of the main burner to be energized, controlling-valve mechanism actuated by said thermostatic shell, and a regulating-valve for said by-pass, having a

threaded terminally-exposed stem, substantially as specified.

8. The combination with a main burner 55 having a supply valve or key and a by-pass, of an adjacent pilot-burner supported by the main burner in communication with said by-pass and having a thermostatic shell extending into the zone of heat of the main burner 60 to be energized, controlling-valve mechanism actuated by said thermostatic shell, said by-pass terminating in a valve-seat in the wall of the main-burner feed-channel, and a regulating-valve having an adjustable stem fitted 65 in the wall of the main-burner feed-channel for axial movement to vary the position of said regulating-valve with relation to the terminal valve-seat of the by-pass, substantially as specified.

9. The combination of a main burner having a lateral bracket, a supply valve or key controlling the gas-supply channel, and a by-pass communicating with said supply-channel and uncontrolled by said valve or key, a 75 pilot-burner having a thermostatic shell fitted in a recess in said bracket in communication with the by-pass, and provided with a valve-seat adjacent to its burner-orifice, and a valve arranged in operative relation with 80 said seat, and having its stem extending through the shell and an alined guide in said bracket, and terminally exposed for adjustment, substantially as specified.

10. The combination with a main burner 85 having a supply valve or key and a by-pass, of an adjacent pilot-burner having a thermostatic shell in communication with said by-pass, and also provided with a controlling-valve seat, a valve arranged in operative relation with said controlling-valve seat, and a valve-stem for the controlling-valve threaded in a fixed guide and terminally exposed for adjustment, and locking devices for securing said stem at the desired adjustment, substan- 90 tially as specified.

In testimony that I claim the foregoing as my own I have hereto affixed my signature in the presence of two witnesses.

JOHN P. FARMER.
